UNITED STATES PATENT OFFICE.

JOHN STARK, OF DROYLSDEN, ASSIGNOR TO ASA LEES & CO., LIMITED, OF OLDHAM, ENGLAND.

SELF-ACTING SPINNING-MULE.

SPECIFICATION forming part of Letters Patent No. 486,945, dated November 29, 1892.

Application filed February 16, 1892. Serial No. 421,741. (No model.)

To all whom it may concern:

Be it known that I, JOHN STARK, overlooker, a subject of the Queen of Great Britain, and residing at Droylsden, in the county of Lancaster, England, have invented new and useful Improvements in Self-Acting Spinning-Mules, of which the following is a specification.

This invention is designed with the object 10 of providing an improved automatic nosing-motion for self-acting mules, by which the required movement at each successive draw of the carriage to give the desired amount of tension to the quadrant-chain is imparted by 15 the shaper-screw.

It consists, essentially, in connecting a pivoted bracket or lever on the upper end of the quadrant-stock, which bears upon the quadrant-chain with the shaper-screw by means 20 of a series of specially-arranged levers with connecting-rods or chain, whereby at each movement of the shaper-screw the pivoted bracket or lever on the quadrant-stock is drawn down to increase the tension of the 25 winding-chain. It will be fully described with reference to the accompanying drawings.

Figure 1 is a front elevation of quadrant and quadrant-stock of the mule with the invention applied; Fig. 2, a plan of Fig. 1; Fig. 3, 30 a front elevation showing modified form of the invention; Fig. 4, a plan of Fig. 3.

The quadrant A, quadrant-stock B, the shaper-screw C, the winding-chain D, the winding-drum D', the head-stock, and other 35 parts of the mule are constructed in the usual way, and I have omitted from the drawings all parts except such as are connected with the present invention.

On the end of the quadrant-stock B is pivoted 40 a bracket E, preferably curved or bent in front elevation with an L-shaped end e, which, as the head of the quadrant-stock is depressed, bears against or upon the winding or quadrant chain D. At the end of the head- 45 stock framing to a bracket attached to the foot of the framing or to the floor I pivot a horizontal lever F, one end of which is attached or connected to a nut G on the shaper-screw C, which moves gradually forward at 50 each movement of the screw. The end of the horizontal lever F is preferably forked to

embrace the screw and abut against the nut G. On the end of the head-stock framing, behind the quadrant A, on a fixed stud a, I pivot a depending arm or lever H, reaching 55 down to the floor. The lower end of the depending lever H engages with or comes in contact with the free end of the horizontal lever F, and as the lever F is moved by the shaper-screw C the motion is transmitted to 60 the depending lever H. The depending lever H and the bracket E are connected together by a connecting-rod or link I, which at one end is formed with a slot i to fit into or engage with a stud h, projecting from the side 65 of the depending lever H and at the other end fits onto a stud e' at the end of the pivoted lever E. The position of the stud h may be adjusted in a slot h' of the lever H, and as the quadrant A is raised the rod or link I 70 slides back over the stud h. This arrangement shows the connection made outside the quadrant, which is what I at present prefer.

When it is desired to place the connecting mechanism inside the quadrant A, I dispense with the depending lever H and connecting-rod or link I and connect the horizontal lever F with the bracket E of the quadrant-stock, as shown in Figs. 3 and 4, by means of a chain or rope K, passing over the 80 guide-pulleys k, affixed to the head-stock foot, the chain being attached to the stud e' at one end and to the stud k' at the other end. The action of the other parts is similar to that already described. As the horizontal lever F 85 is moved by the shaper-screw C the pivoted bracket E is drawn down upon the winding-chain D. It will also be obvious that instead of dispensing with the depending lever H the link I only may be removed and the 90 lever H connected to the bracket E by a chain.

What I claim as my invention, and desire to secure by Letters Patent, is—

1. In a self-acting mule, the combination, 95 with the quadrant A, quadrant-stock B, winding-chain D, and shaper-screw C, of the horizontal pivoted lever F, moved forward thereby at each turn of the screw, the tightening-lever E on the quadrant-stock provided with an L-shaped end which comes in contact 100 with the winding-chain D, and a non-rigid connection between the lever F and the lever

E, whereby the movement of the one is transmitted to the other, substantially as described.

2. A nosing-motion for self-acting mules, comprised of a tightening lever or bracket E, pivoted to the quadrant-stock and provided with an L-shaped arm to bear upon and tighten the winding-chain, a horizontal pivoted lever F, which is actuated by and transmits motion from the shaper-screw, and a depending lever H and link I, which connect together the levers E and F and transmit the movement of the one to the other, in combination with the quadrant-stock B, winding-chain D, and shaper-screw C.
- 15 3. In a self-acting mule, the combination, with the quadrant A, quadrant-stock B, and shaper-screw C, winding-chain D, and winding-drum D', of the lever E, pivoted to the quadrant-stock and provided at the end 20 with a pin e', the horizontal pivoted lever F, actuated by the shaper-screw, the nut G, the depending lever H, provided with a stud h,

which engages with the link I, and the link I, provided with a slot i, which connects the levers H and E, substantially as described. 25

4. In a self-acting mule, the combination, with the quadrant-stock B, the winding-chain D, the pivoted bracket or lever E on the upper end of the quadrant-stock which bears upon the quadrant-chain, and the shaper-screw C, provided with a nut moving thereon, of the horizontal pivoted lever F, connected to the lever E by a non-rigid connection to move or gradually alter the position of the tightening-lever E, substantially as described. 30 35

In testimony whereof I have signed my name to this specification, in the presence of two subscribing witnesses, this 1st day of February, 1892.

JOHN STARK.
